(57) **CLAIM**

The ornamental design for a beverage vessel as shown and described.

DESCRIPTION

FIG. 1 is a top front perspective view of a beverage vessel according to the present design.

FIG. 2 is a bottom rear perspective view of the beverage vessel of FIG. 1.

FIG. 3 is a front view the beverage vessel of FIG. 1.

FIG. 4 is a back view of the beverage vessel of FIG. 1.

FIG. 5 is a left side view of the beverage vessel of FIG. 1.

FIG. 6 is a right side view of the beverage vessel of FIG. 1.

FIG. 7 is a top view of the beverage vessel of FIG. 1.

FIG. 8 is a bottom view of the beverage vessel of FIG. 1; and,

FIG. 9 is a top front perspective view of the beverage vessel of FIG. 1, shown with a broken line lid for clarity of disclosure.

The broken lines are directed to unclaimed features of the beverage vessel and form no part of the claimed design.

1 Claim, 9 Drawing Sheets
